PULLEY CLEANING CONSTRUCTION

Raymond Q. Armington, Shaker Heights, Ohio,
assignor to The Euclid Road Machinery Co.,
Euclid, Ohio, a corporation of Ohio

Application June 6, 1945, Serial No. 597,793

2 Claims. (Cl. 198—229)

1

This invention relates to improvements in pulley cleaning construction and more particularly to the removal of dirt from the pulley of a conveyor loader working under dirty conditions.

An object of the present invention is to provide a blade for scraping dirt from a pulley of the type described together with novel rotating spring means for carrying the dirt away.

Another object of the present invention is to provide cleaning means for a pulley driven by the rotation of the pulley itself.

Other objects of the invention include the novel construction and arrangement of the parts whereby the pulley is efficiently cleaned, the dirt is efficiently carried away, and the parts are so constructed and arranged that they will operate for a long time without interruption even when subjected to severe operating conditions.

Other objects and advantages of my invention will be apparent from the accompanying drawings and description, and the essential features thereof will be summarized in the appended claims.

In the drawings:

Fig. 1 is a top plan view of a portion of a belt conveyor adapted to handle dirt or the like showing one embodiment of my invention and with certain parts broken away to more clearly show the construction;

Fig. 2 is a side elevational view of the device of Fig. 1 with one of the beams broken away to more clearly show the conveyor;

Fig. 3 is a top plan view, enlarged, of a portion of Fig. 1 and taken in the position of line 3—3 of Fig. 4, with certain of the parts being shown in section to more clearly illustrate the construction;

Fig. 4 is an elevational view of the right-hand end of the device of Fig. 3; while

Fig. 5 is a view taken along the line 5—5 of Fig. 3.

Certain features of my invention are applicable to many types of apparatus, but I have chosen to illustrate as one embodiment the application of my pulley cleaning apparatus as applied to a digging and loading device which is fully disclosed in the copending application of Raymond Q. Armington and George E. Armington, Serial Number 593,412, filed May 12, 1945, to which reference may be had for a more complete description of the loader device. It is sufficient to state here that digging and dirt-guiding devices generally indicated by the reference character 10 herein are mounted on beams 11 which cause the digging devices to enter into the ground as the equipment

2

moves thereover. Embodied in this larger apparatus is the conveyor 12 consisting of the frame 12a, a tail pulley 12b and a head pulley (not shown), there being an endless conveyor belt 13 passing over the head and tail pulleys and driven by means at the head pulley, not disclosed here but fully disclosed and described in the copending application mentioned above. Preferably the upper run of the conveyor passes over a series of troughing idlers 14, it being understood that the dirt travels on the upper run of the conveyor belt from the lower left-hand corner of Fig. 1 diagonally upwardly toward the right-hand end of Fig. 1 and on beyond this point to discharge into a vehicle which carries the dirt away as described in the copending application mentioned. Preferably also, the lower or return run of the conveyor will travel on plain cylindrical idler rolls to keep the conveyor belt from sagging too much. Preferably also, a dirt shed (not shown) is provided between the upper and lower runs of the conveyor to insure that any dirt dropping off the upper run of the conveyor will be discharged sideways out the openings 15 in the conveyor frame. This dirt shed is of a usual type of shallow inverted V-form in section, the central ridge of the shed running parallel with the center line of the upper run of the conveyor and the sides thereof sloping toward the openings 15 on each side of the conveyor frame.

Devices of the above-described type do not operate well unless dirt is prevented from clinging to and building up upon the tail pulley 12b. To prevent this, the outer cylindrical surface of this pulley is hardened and provided with a smooth finish, and a scraping blade 16 of hardened metal engages the surface of the pulley, as best seen in Fig. 4, substantially tangentially to the cylindrical pulley surface and on the side thereof where the surface of the pulley is moving downwardly as the pulley rotates in the direction of the arrow of Fig. 4 due to the travel of the belt 13 as driven by the head pulley mentioned above. Preferably the blade 16 is thin and resilient having the characteristics of spring metal for a purpose later described.

A dirt pan 17 is provided for collecting the dirt from the blade 16. This pan is generally of the form of a long hollow cylinder having a cylindrical wall around substantially three quarters of the perimeter of the cylinder, leaving the open space 17a directed toward the point where the blade 16 engages the pulley surface. The side of the pan nearer the pulley is bent out of the generally cylindrical form to lie parallel to the blade 16

along the pan portion 17b, and the blade 16 is secured to this part of the pan. Preferably, but not necessarily, the left-hand end of the blade 16, as seen in Fig. 3, is provided with a notch 16a opening toward the adjacent end of the blade and adapted to receive a stud 18 which is fixed on the pan portion 17b where it extends to the left (Fig. 3) beyond the generally cylindrical portion of the pan 17. This stud 18 is rigid with the pan and has an enlarged head lying on the pulley side of blade 16 so as to firmly hold the blade there. At the opposite end a stud bolt 19 passes through blade 16 into the pan portion 17b to fix that end of the blade. Preferably the blade 16 is provided with parallel top and bottom edges 16b and 16c, and the notch 16a and the hole which receives stud bolt 19 are both midway between edges 16b and 16c so that the blade is reversible.

The left-hand end of pan 17, as viewed in Fig. 3, is substantially closed by the end plate 17c to which is rigidly secured a sleeve 17d which supports this end of the pan in a manner presently described. The right-hand end of the pan, as viewed in Fig. 3, is open for the discharge of dirt, and this end of the pan is welded to a mounting flange 20 through which pass bolts 21 to secure the same to the conveyor frame. Preferably also, an L-shaped plate 22 extends substantially the full length of the blade 16 with the longer leg of the L parallel to and engaging the blade to support it firmly. This L-shaped plate is welded to the pan 17 rigidly and provides a pocket into which the blade 16 is slipped. Preferably, but not necessarily, a small portion of the top of the dirt pan is cut away near the dirt-discharge end, as best seen in Fig. 3, to insure that no dirt piles up on top of the pan but falls directly into the pan for discharge by the means presently described.

The means for discharging the collected dirt out of the pan 17 comprises a long helical spring 23, the outer elements of which generally conform to the bottom of the dirt pan. Means is provided for rotating this spring in a direction to carry the dirt out the open end of the pan. I provide a novel drive means which utilizes the normal rotation of the tail pulley 12b. Mounted on the left end of this pulley, as viewed in Fig. 3, is a pinion 24 which is keyed to the pulley shaft to rotate therewith. Meshing with this pinion is the large gear 25 which in turn rotates shaft 26 which is connected through a universal joint device 27 to the shaft 28 which is rigidly connected with the spring 23. Suitable bearings and gear case are provided for the pinion 24 and gear 25, as shown in the drawings, but these are of usual and known type. The details of the universal joint device 27 need not be described here as they form no part of the present invention and merely provide an efficient drive even though there is slight misalignment of shafts 26 and 28. It will be noted that the shaft 28 passes through the hollow central portion of the sleeve 17d, these parts being coaxial with the helical spring 23. Spring 23 is wrapped around and welded to collar 30 which is threaded on the inner end of shaft 28. It results from this construction that as the belt 13 pursues its normal course of travel, the pulley 12b is rotated, and by the gear connections just described causes rotation of spring 23 in a direction to discharge dirt out the open end of the pan 17.

The details at the left end of pan 17, as viewed in Fig. 3, will now be described. Secured to a portion of the conveyor frame marked 12c is a

bracket 31 which, as best seen in Fig. 5, has a vertical wall 31a parallel to the pan portion 17c, and above this an inclined portion 31b which is sloped so as to form a dirt shed. This bracket is stiffened and held firmly in place by means of a tubular strut 32 which is welded between the bracket 31 and an L-shaped plate 33 which in turn is rigidly secured to the part 12c by means not shown. In the inclined wall 31b is inserted a sleeve 34 which extends clear through the wall and is welded thereto. The inner diameter of this sleeve is chosen to fit the outer diameter of the sleeve 17d, previously described, so as to firmly support the end of the dirt pan. The shaft 28 then passes through the sleeve 34 and through the hollow sleeve 17d as clearly shown in Figs. 3 and 5.

It will be noted that the above construction permits the tilting of pan 17 about the sleeve 17d as a pivot. In assembling the parts, the pan is so tilted to move the left-hand end of scraper blade 16 in stressed position against the pulley surface 12b, and thereafter the other end of the pan is secured in place by the bolts 21 so as to yieldingly press the blade 16 at all points against the pulley surface 12b.

It will be noted that the driving connections, previously described, and more clearly shown at the left end of Fig. 3 and housed in the gear casting 35, are placed far enough to one side of the conveyor belt 13 so that dirt falling from the belt is not near the driving parts. It will be noted also that all of the parts are so housed and protected that dirt does not easily get into the moving parts, and by this means the pulley is kept continuously clean, and the dirt is continuously moved away from the parts which might be injured thereby.

Referring to Fig. 5, it will be noted that any dirt falling off the upper run 13a of the conveyor belt will be deflected by the dirt shed 31b and fall to the ground instead of falling upon the lower run 13b of the belt.

What I claim is:

1. In combination with a conveyor and a rotatable pulley over which said conveyor passes, a dirt pan adjacent said pulley, said pan being a major circumferential portion of a hollow cylinder positioned with its axis parallel to the axis of said pulley and with an open side of said cylinder substantially tangential to said pulley on a side of the latter which rotates downwardly toward said pan, a scraper blade of spring metal resiliently engaging said pulley on said side thereof, said blade connected with the open side of said cylindrical pan, a helical spring in said pan extending longitudinally thereof, said spring substantially conforming to the inner walls of said pan, said pan having an open end, and means for rotating said spring in a direction to carry dirt out said open end of said pan, said last named means having an operative connection with said pulley to provide driving means therefor.

2. In combination with a conveyor and a rotatable pulley over which said conveyor passes, a dirt pan adjacent said pulley, said pan being a major circumferential portion of a hollow cylinder positioned with its axis parallel to the axis of said pulley and with an open side of said cylinder substantially tangential to said pulley on a side of the latter which rotates downwardly toward said pan, a scraper blade of spring metal resiliently engaging said pulley on said side thereof, said blade rigidly connected with the

open side of said cylindrical pan, a helical spring in said pan extending longitudinally thereof, said pan having an open end, interfitting bearing members on said conveyor and on said pan at the end opposite said open end for mounting said pan oscillatably about said bearing members, other means nearer the open end of said pan for holding the same with said scraper blade resil-

iently engaging said pulley, a stub shaft rigid with said spring and coaxial therewith, and means for rotating said shaft in a direction to cause said spring to carry dirt out said open end of said pan, said last named means having a driving connection with said pulley.

RAYMOND Q. ARMINGTON.
